UNITED STATES PATENT OFFICE.

WAU DELL REYNOLDS, OF GREENVILLE, SOUTH CAROLINA.

COMBINATION-LOCK.

1,320,919.

Specification of Letters Patent.

Patented Nov. 4, 1919.

Application filed March 11, 1918. Serial No. 221,750.

To all whom it may concern:

Be it known that I, WAU DELL REYNOLDS, a citizen of the United States, residing at Greenville, in the county of Greenville, 5 State of South Carolina, have invented certain new and useful Improvements in Combination-Locks; and I do hereby declare the following to be a full, clear, and exact description of the invention, such as will 10 enable others skilled in the art to which it appertains to make and use the same.

This invention relates to combination locks and has for its object to provide an improved structure in which a plurality of 15 keys, successively introduced through the same key-hole, will be required to release the locking bolt.

In the accompanying drawings;

Figure 1 is an elevational view of a lock 20 embodying the present invention.

Fig. 2 is an elevational view thereof with the face plate of the lock casing removed.

Fig. 3 is a transverse sectional view 25 through the casing on the line 3—3 of Fig. 2.

Fig. 4 is a sectional view on line 4—4 of Fig. 2.

Fig. 5 is a detail sectional view on the line 5—5 of Fig. 4.

Fig. 6 is a perspective view of one of the 30 tumblers of the lock.

Fig. 7 is a perspective view showing the tumbler actuating keys in mutually juxtaposed position.

Fig. 8 is a perspective view of the bolt 35 retracting key.

Referring now more particularly to the accompanying drawings, there is provided a flat casing 5 of the general type used in lock construction and having bolt apertures 40 6 in the end portions of one of its side edge walls. Slidably mounted in the casing to project through one of these openings is a latch bolt 7 resiliently urged by the spring 8 to project in locking position, and having a recess 9 receiving an arm 10 on a knob shaft 11 whereby it may be retracted, the bolt and knob shaft being preferably disposed in the lower portion of the casing.

A locking bolt 12 is slidably mounted in 50 the upper portions of the casing to project through the upper bolt aperture, the mounting for said bolt preferably comprising spaced transverse plates 13 and 14 secured to the side wall of the casing, and on

which the bolt rests. For moving the bolt 55 to extended and retracted positions, a shaft 15 is transversely journaled in the casing below the forward end of the bolt and carries an upstanding arm 16 engaged in a notch 17 in the bottom of the bolt to provide a rocking connection. The face side of the casing is slotted at 17, and the adjacent end of the shaft 15 is recessed at 18 for the reception of the head of a removable key 19, shown in Fig. 8, to effect bolt shifting 60 rotation of the shaft.

The permutation mechanism for controlling the operating of the bolt under influence of this key actuated shaft comprises a pair of tumbler disks 20 and 21 having 70 laterally projected hub sleeves 22 and 23 at corresponding sides, the sleeve 23 of the disk 21 being of materially greater diameter than sleeve 22. The sleeve hub 22 is mounted on a bearing sleeve 24 and carried 75 by projecting inwardly from one side wall of the casing. Loosely engaged about the sleeve hub 22 is a bearing sleeve 25 for the sleeve hub 23, this bearing sleeve 25 being carried by a plate 26 which extends between 80 the permutation disks and is secured to the rear edge wall of the casing. A sleeve 27 embraces the hub 23 and extends to the opposite side casing wall. Thus the permutation disks are mounted for independent rotation and held in assembled position. It is noted that the free edge of each of the disk hubs extends inwardly of its bearing sleeve, and said inwardly extended portion of each hub is provided with a notch 28 engageable 85 by a key inserted in the casing for turning the disk. As shown more particularly in Fig. 7, the key for the hub 22 comprises a shank 29 having a notch engaging wing 30 adjacent its work end, and a key for the hub 23 comprises a shank 31 having a wing 32 adjacent its work end and spaced inwardly a distance greater than the distance of the wing 30 from the end of its shaft, this wing 32 being also of greater length 90 than the wing 30. Both keys are inserted through a keyhole 33 in the casing wall adjacent the retaining sleeve 27, and to prevent possible insertion of an improvised actuating member through the keyhole to turn the tumbler disks, a transverse partition 34 is provided in the sleeve 27 having a keyhole 35 extending in a direction opposite to 95 100 105

the keyhole 33, and with its shank receiving portion in alinement with the shank receiving portion of the keyhole 33. Thus, to turn the disks, each of the keys 29 and 5 31 is inserted through the keyhole 33, turned and inserted through the keyhole 35, and then engaged with the notch of its corresponding disk hub.

Each of the permutation disks is provided 10 in its periphery with a series of spaced notches 36 of slight depth, and with a single radial notch 37 of a depth substantially equal to the distance which the locking bolt 12 moves from extended to retracted positions. Extended inwardly from the bolt 12 is an arm 38 which carries at its free ends a lateral finger 39 adapted to engage in the notches 38 when in alinement therewith and with each other to permit a retractile 15 movement of the bolt, and adapted to abut the peripheries of the disks in other relative positions of their notches 38 to prevent retractile movements of the bolt.

To determine the position of each of the 20 tumbler disks upon engagement of its corresponding key in the notch of its hub, each key has fixed thereon a disk 41 having an annular series of symbols 42 on its periphery coacting with a pointer 43 on the casing wall 25 when the key is inserted in the casing. It will however be understood that the indicating means may be of conventional nature comprising a symbol disk on the casing and a pointer on the key, such conventional arrangement being obvious and hence not 30 specifically illustrated.

An exceedingly simple, and durable and readily assembled permutation lock has thus 35 been provided, which affords a high degree of protection against unauthorized actuation, by reason of the plurality of key members employed in conjunction therewith and by reason of the means preventing actuation of the tumbler disks by an improvised 40 tool. The notches 36 prevent the detection 45 of the combination by noting the "click" usually present in locks of this nature and caused by registry of the tumbler notch with its engaging member, since said notches 50 produce the same effect on the tumbler engagement member as do the receiving notches 37, except when such notches 37 are in alinement therewith.

The present lock may be associated with 55 doors, and if desired, mortised thereinto in

the manner of ordinary key and knob actuated locks.

What is claimed is:

1. A combination lock comprising a bolt, a plurality of superimposed disks adjustable 60 with respect to each other, said bolt and disks having coöperating means for permitting releasing movement of the bolt in pre-determined positions of the disks and bolt, the disks having hubs disposed one within 65 the other and projecting one beyond the end of the other, said ends being notched, the notch of the projecting hub terminating short of the end of the other hub, and a casing inclosing the bolt and disks and 70 having a key-hole leading to the notched hubs.

2. A lock comprising a casing, a bolt movably mounted in the casing, a pair of disks coaxially mounted within the casing, said 75 disks having each a hub which are disposed one within the other, the outer hub projecting beyond the end of the inner hub and the outer ends of the hubs being notched, with the notch of the outer hub terminating short 80 of the end of the inner hub, said disks and bolt being correlativey constructed to permit of sliding movement of the bolt when the disks are in a pre-determined position, the casing having a key-hole and a web 85 within the casing between the key-hole and the disks and having a key-hole out of registration with that of the casing.

3. A combination lock comprising a casing, a disk mounted in the casing and having 90 a hub projecting from one face and provided with a terminal notch, a bearing carried by the casing and in which the hub is rotatable, a second disk encircling said bearing and hub and having a hub projecting 95 beyond the end of the first named hub and provided with an end notch terminating short of the first named hub, a sleeve carried by the casing and encircling the hub of the second disk, a casing within the inclosure of the sleeve having a key-hole, and a partition in the sleeve parallel with the disks and having therethrough a key-hole out of 100 registration with the first named key-hole.

In testimony whereof, I affix my signature, in the presence of two witnesses.

WAU DELL REYNOLDS.
